UNITED STATES PATENT OFFICE

116,436

DESIGN FOR A TEXTILE FABRIC

Michael Simeone, New York, N. Y.

Application April 26, 1939, Serial No. 84,572

Term of patent 3½ years

To all whom it may concern:

Be it known that I, Michael Simeone, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein

The figure is a plan view of a piece of textile fabric showing my new design.

The unit is shown between the lines A—A.

The stripe B is of a color which contrasts with

that of the stripe A, and each half of the unit above and below the stripe B is identical.

The drawing shows a portion of the fabric having its lower edge turned over, showing the rear face.

The design consists of a series of groups of variegated cord stripes arranged on the face of the fabric, each group being alternately provided with contrasting colors, as shown.

I claim:

The ornamental design for a textile fabric, substantially as shown, and described.

MICHAEL SIMEONE,
